Inventor:

John S. Rathbone.

UNITED STATES PATENT OFFICE.

JOHN S. RATHBONE, OF ASHEVILLE, NORTH CAROLINA.

TAG AND TAG-FASTENER.

SPECIFICATION forming part of Letters Patent No. 361,451, dated April 19, 1887.

Application filed December 15, 1886. Serial No. 221,698. (No model.)

To all whom it may concern:

Be it known that I, JOHN S. RATHBONE, residing at Asheville, in the county of Buncombe, State of North Carolina, have invented 5 a new and useful folded metal strip for application to tags, cards, or paper slips, and to be used as a handle or stick, of which the following is a specification.

My invention consists of a folded metal strip, 10 pointed or otherwise, and the application thereof to a tag, card, or paper slip, to be used as a stick or handle.

The attachment or fastening of the folded metal strip to a tag, card, or paper slip is accomplished by placing the tag, card, or paper slip between the folded metal, then to tightly compress the metal, and, finally, to slightly indent or punch the metal over the place where the tag, card, or paper slip is inserted, as set 15 forth in the drawings, *viz.*:

Figure 1 shows the folded metal strip A. Fig. 2 shows the method of attachment or fastening (C C) of the folded metal strip A to a tag, card, or paper slip, B. Fig. 3 shows the 20 combination of the folded metal strip A and the tag, card, or paper slip B.

The tag B may be of any suitable form, and

it is attached to the stick A, which consists of a folded piece of metal, by laying the edge of the tag in the fold of the metal stick and then compressing the metal together and indenting it, as at C C. The end of the metal stick is preferably sharpened, so that it may readily be inserted in a package, bale, or bundle, &c., as required. 30

I am aware that prior to my invention tags, cards, and paper slips have been used with wooden sticks for handles, fastened in various ways.

I claim—

1. The herein-described tag-holder, consisting of a strip of sheet metal folded upon itself to form a holding-groove and pointed at one end to serve as a means of attachment, substantially as described. 40

2. The combination of a tag-holder, consisting of a metallic binding-strip folded and pointed, as described, and a card or tag held between the foiled portions of the strip by the indentations, substantially as described. 45

JOHN S. RATHBONE.
